Primary Examiner — Paula Allen Greene(74) *Attorney, Agent, or Firm* — DLA Piper LLP (US)(57) **CLAIM**

The ornamental design for karaoke microphone as shown and described.

DESCRIPTION

FIG. 1 is a perspective view of a karaoke microphone showing the new design.

FIG. 2 is a front elevational view thereof.

FIG. 3 is a back elevational view thereof.

FIG. 4 is a left side elevational view thereof.

FIG. 5 is a right side elevational view thereof.

FIG. 6 is a bottom plan view thereof; and,

FIG. 7 is a top plan view thereof.

The broken lines depict portions of the karaoke microphone that forms no part of the claimed design.
